MACHINE FOR APPLYING REINFORCING
FABRIC TO INNER SOLES

John A. Scott, St. Louis, Mo.

Application December 17, 1936, Serial No. 116,440

4 Claims. (Cl. 12—20)

This invention relates to methods of and machines for applying reinforcing fabric to the lipped surfaces of leather inner soles.

The main object of the invention is to provide a method of applying a rubber latex cement to the lipped surface of a leather or composition inner sole under pressure sufficient to cause the cement to penetrate the surface fibers of the inner sole and thereafter applying the dried cemented side of a prepared strip of reinforcing fabric to the moist cemented surface of said inner sole under pressure sufficient to cause maximum adherence of the fabric to the inner sole.

Another object of the invention is to provide a machine adapted to carry out expeditiously the method just described.

Other objects of the invention will become apparent as the detailed description thereof proceeds.

20 In the drawings:

Figure 1 is a perspective view of the machine; Figure 2 is a top plan of the machine shown in Figure 1, with parts removed and other parts shown in section, to illustrate details of construction;

Figure 3 is a vertical section taken on the line 3—3 of Figure 2;

Figure 4 is a vertical transverse section taken on the line 4—4 of Figure 2;

Figure 5 is a fragmentary section, to an enlarged scale, also taken on the line 4—4 of Figure 2, and illustrating the upper part of the machine as shown in Figure 4;

Figure 6 is a vertical section taken on the line 6—6 of Figure 2;

Figure 7 is a horizontal section taken on the line 7—7 of Figure 4;

Figure 8 is a vertical section taken on the line 8—8 of Figure 4;

Figure 9 is a fragmentary detail in section, of one of the operating valves of the machine;

Figure 10 is a horizontal section taken on the line 10—10 of Figure 9;

Figure 11 is a fragmentary perspective view, to an enlarged scale, of a device for spraying latex against the lipped face of the inner sole;

Figure 12 is a section taken on the line 12—12 of Figure 11; and

Figure 13 is a fragmentary detail of a fabric cutter forming a part of the machine.

As shown in the drawings, the machine comprises a casing designated generally by the reference numeral 14. This casing includes side walls 15 and 16, rear wall 17, front wall 18 and 55 an intermediate wall or partition 19 extending be-

tween the front and rear walls substantially parallel to the walls 15 and 16. This partition 19 divides the casing into two chambers designated generally by the reference numerals 20 and 21.

The chamber 21 (see Figure 3) is provided with a partition 22 extending horizontally between the partition 19 and the side wall 16, but sloping downwardly from the rear wall 17 toward the front wall 18, where part of it is bent to form a horizontal portion or sump 23 provided with an outlet 24 located directly above a receptacle 25 adapted to receive excess latex resulting from a spraying operation. The wall 18 is provided with an opening 26 through which the receptacle 25 may be removed or replaced whenever found necessary or desirable. The receptacle 25 is supported when in use, on a horizontal strap or plate 27 supported by and extending between the walls 16 and 19. A flange 28 turned upwardly from the rear edge of the plate 27 serves to limit the inner movement of the receptacle 25. A coil spring 29 detachably secured to the walls 16 and 19 across the opening 26, holds the receptacle 25 in position under the outlet 24.

At the upper part of the chamber 21, a horizontal partition 30 extends between the walls 16 and 19 and is suitably riveted or otherwise secured at its opposite ends to said walls. The partition 30 is arranged below the top edge 31 of the chamber 21 to form a recess receiving the lower tank part 32 of a bottle or receptacle support having at its center a substantially cylindrical member 33 adapted to receive and position the mouth 34 of a receptacle 35.

As shown, the receptacle 35 is a large glass bottle through which the contents may be seen. To support this bottle properly in inverted position above the tank 32, there is provided a bottle rest 36 provided with downwardly extending lugs 37 which fit snugly along the inside faces of the tank 32. The member 36 is provided at its center with an upturned cylinder 38 of greater diameter than, and concentric with the cylindrical member 33 in the tank 32. This cylinder 38 serves as a support for the neck of the bottle near its widest part, and holds the bottle vertically inverted with the mouth 34 extending within the cylinder 33 and spaced from the bottom of tank 32, the cylinder 33 being provided with a slot 39 through which the liquid from the bottle 35 may flow into the tank 32. This arrangement is of a self-sealing type commonly used in dispensing apparatus, and is designed to maintain the liquid in the tank 32 at a substantially constant level above the bottom of the tank 32.

The member 36 is provided with a slot 40 near the front end thereof, to receive and permit the movement therethrough of a pipe 41 designed to withdraw latex from the tank 32. The lower end 5 of the pipe 41 rests upon the bottom of tank 32 and is cut away laterally to form an inlet 42 for the latex. The upper end of the pipe 41 is connected by an elbow 43 to one end of a pipe 44, the other end of which is connected to a spray fitting 10 45. The fitting 45 is provided with a passageway 46, leading to a spray tube 47 detachably connected to the fitting 45. The tube 47 is provided with a flat elongated aperture 48 which extends centrally across the tube; and upper corner of the 15 tube 47 is beveled downwardly as shown at 49, to direct air under pressure emerging from a nozzle 50 formed at the lower end of a pipe 51 connected to a source of supply of air under pressure. The nozzle 50 and the aperture 48 are arranged perpendicularly to and slightly spaced from each other. This construction effects a lateral spreading of the spray of cement as it issues from the spray aperture 48.

The pipe 51 is connected at its upper end to an 25 elbow 52 which, in turn, is connected to one end of a curved pipe 53 having its other end connected by an elbow 54 to a pipe 55 extending across the front of the machine to the side 15. At the side 15, the end of the pipe 55 is connected by an elbow 30 fitting 56 to a valve 57 used to operate a cutter mechanism hereinafter described. A T-fitting 58 controlled by a manually operated valve 59 connects the fitting 56 to an air pressure gauge 60, which is also connected by a pipe 61 to a compression 35 chamber 62 suitably supported within the lower end of the chamber 20.

A compressor 63 is shown in Figures 1 and 4 as supported by the compressed air storage chamber 62, and as operated by a motor 64. The motor and 40 compressor shafts 65 and 66, respectively, are provided with pulleys connected by a belt 67 to impart rotation of the motor shaft to the compressor shaft. The belt 67 also extends around a pulley 68 secured to the ends of a shaft 69, 45 which is suitably journaled in the front and rear casing to rotate a fan 70 secured to the end of the shaft 69 opposite to the end on which the pulley 68 is mounted. A guard 71 is secured to the rear wall 17 to enclose the aforesaid pulleys and belt, 50 and also to enclose a ventilating aperture 72 formed in the aforesaid rear wall 17.

There is nothing novel in the compressor, motor and fan mechanisms per se. The fan, however, is employed in this case to draw excess spray of 55 latex from the cementing chamber which would otherwise be discharged into the room containing the machine, and would make operation practically impossible.

To effect withdrawal of excess latex spray from 60 the spraying chamber, the intermediate wall 19 is provided, above the partition 22, with an aperture 73 leading to a chamber 74 provided with a series of horizontal plates 75, 76, and 77, each of which has secured thereto a series of zig zag baffle 65 plates parallel to each other. As shown in Figures 4 and 7 of the drawings, there are three series of baffle plates depending from the plate 75. It is to be noted that the plate 75 extends from the rear wall 17 to a line substantially flush with the front 70 wall 18 where its front edge 78 is adapted to contact with the inner face of a door 79, shown in Figure 1 of the drawings as hinged to the side wall 15. The inner ends of the baffle plates 80, 81 and 82 on plate 75 terminate at a distance from the 75 rear wall 17 slightly greater than the distance

of the forward edge of the aperture 73 from the said rear wall. This construction permits the spray mist to be drawn freely through the aperture 73 and through the zig-zag passageways formed by the series of baffle plates 80, 81 and 82. 5

The second series of zigzag baffle plates 84, 85 and 86 are secured to and depend from the plate 76 which forms a support for the upper series of baffle plates just described. It is to be noted that the forward edge of the plate 76 terminates at 10 some distance to the rear of the inner face of the door 79 to form a passageway for the downward flow of latex mist from the upper series of baffle plates to the intermediate series 84, 85 and 86.

A lowermost series of baffle plates, similar to the 15 other series, is secured to and depends from the plate 77, and is supported by the horizontal wall 80 which forms the top of the chamber containing the motor and compressor mechanism. As shown in Figure 4, the rear edge of the plate 77 20 terminates from the rear wall 17, in order to provide a downward passage for the mist of latex passing through the superposed series of baffle plates secured to the plates 75 and 76.

Arranged between the partition 18' which 25 forms the front wall of the compressor chamber and the door 79, is a vertical plate 87. A series of zigzag baffle plates 90 is secured to the plate 87, and the entire structure is arranged with the series of baffle plates against the wall 18' in such 30 position as to provide a corresponding series of zigzag passageways communicating at the lower end of the wall 18' with the fan 70, which communicates with a duct 91 leading to the atmosphere. The door 79 is provided near its striking 35 edge with a suitable locking mechanism operated by a handle 92 for the purpose of securing all the baffle plate structures properly within the main casing 14.

It will be obvious from the structure disclosed 40 in Figures 2, 3, 4, 7, 8 and 9, that when the fan 70 is in operation, the mist of latex will be drawn from the chamber 20 through the aperture 73 in zigzag paths across and downwardly of the baffle plates supported by the plates 75, 76 and 77, 45 through the passageways between the vertical baffle plates 90, and to and through the fan and the outlet 91 to the atmosphere. In actual practice, it has been found that most of the excess latex is deposited on the horizontal series of 50 baffle plates in the form of a thin skin which can be readily removed from the plates about once a week. If it were not for this removal of the latex vapors, it would be impossible to operate the machine because of the flow of this latex mist 55 under pressure into the room containing the machine.

The upper part of the latex chamber is provided with a cover designated generally by the reference numeral 91'. This cover comprises a top 92 bent to form a downwardly extending flange 93 which, when in position, rests at its lower edge on the upper face of the table 94 which forms the top of the casing 14 and a support for mechanism operating on a strip of fabric to be 65 applied to the sprayed surfaces of inner soles.

The other edge of the cover 91' is turned downwardly to form a flange 95 cut away to provide a passageway through which an inner sole may be readily introduced laterally into the spraying chamber for the purpose of applying latex to the lipped surface of said inner sole. A rear wall 96 connecting flanges 93 and 95 of the cover 91' is provided with a slot 97 to receive the pipe 44, and enable the cover 91 to be properly posi- 70 75 75

tioned with its said wall 96 in contact with the forward edge of the horizontal partition 30, and thereby form a stop holding the bottle supporting members 32 and 36 in proper position in the machine. A shelf 98 is detachably secured to the wall 16 of the machine substantially level with a downwardly inclined flange 99 formed on the upper edge of the wall 16 where it projects into the spraying chamber. The lip or flange 99 forms 10 a convenient rest for supporting the smooth surface of the lipped inner sole in proper position under the spraying nozzles 48 and 50.

The top 94 forms a supporting base for mechanism adapted to cut strips of fabric mounted on rolls into predetermined lengths. This mechanism is supported on castings 100 and 101, the casting 100 being substantially flush with the side 15 of the casing of the machine, while the casting 101 is substantially flush with the intermediate wall 19. The upper parts of the front ends of the castings 100 and 101 are secured to each other by a transverse angle iron 102. The horizontal flange 103 of the angle iron 102, is provided with a pair of lugs 104 and 105, apertured to receive a pivot pin 106. The lugs 104 and 105 are spaced apart to receive between them apertured bosses 107 and 108 pivoted to the pin 106 and having projecting therefrom the arms 109 and 110, respectively. The free ends of the arms 109 and 110 are provided with laterally projecting pins 111 and 112 adapted to receive rolls of fabric 113 and 114, respectively. Lugs 107 formed on the bosses 107 and 108 limit the movements of the arms 110 and 111 rearwardly so as to maintain the pins 111 and 112 substantially in alignment when in operative position.

A roll 115 is mounted on the castings 100 and 101 to rotate about a substantially horizontal axis. The strips of fabric are wound around the roll 115, and around a roll 116 mounted to rotate in slots formed in the free ends of a pair of links 117 and 118, having their other ends pivoted to swing about a pivot rod 119 extending horizontally between and suitably secured to the castings 100 and 101. A rod 120 extends radially from the center of the rod 119 through an aperture 121 formed diametrically through the center of the roll 116.

The free end of the rod 120, where it projects through roll 116, is screwthreaded to receive a thumb nut 122, one wing of which is provided with an aperture 123 receiving one end of a tension spring 124, the other end of which is secured to an eye 125 fixed to a casting 126 integral with the angle iron 102.

A stop 127 is secured to the inner wall of casting 101 to limit the rearward movement of the links 117 and 118 and the roll 116 carried thereby.

A plate 128 is mounted to reciprocate in the space between the castings 100 and 101. At its opposite edges the plate 128 is provided with upturned flanges 129 and 130 which project beyond the rear edge 131 of the plate 128 and are apertured to pivot on the opposite ends of the roll 116, which therefore forms a pivotal support for the rear end of the plate 128. The forward end of the plate 128 is slidably supported by the heads of machine screws 132 screwthreaded into a base plate 133 and locked in adjusted position by lock nuts 134. The base plate 133 is suitably secured to, or formed integral with the castings 100 and 101, at a distance above the lower edges of said castings to form, with the top 94, a slot 135 through which a plate 136 is mounted to reciprocate.

The plate 136 has angle irons 137 and 138 secured at the opposite side edges of its lower face, the vertical flanges of which are supported by the channeled peripheries of anti-friction rollers 139 pivoted to rotate on the upturned flanges 139 and 140 of a plate 141 secured by screws 142 to the base plate 94. 5

A stop 143 is adjustably secured to the plate 136 to contact with the toe of an inner sole, and to determine the length of fabric to be cut off from the strip in accordance with the length of said inner sole or that portion thereof which extends from the heel part to the raised lip at the toe part. A flange 144 on the lower edge of stop 143 is provided with slots (not shown) to receive the screws 145 threaded into the plate 136 for the purpose of securing the stop 143 in adjusted position. The upper edge of the stop is also provided with a flange 146 to limit the movements of any inner sole which happens to be supported on plate 136. 20

The plate 128 has a strap 147 secured at its opposite ends to the opposite edges of the plate and spaced apart from the face of the plate to form a slot 148 adapted to receive and guide a strip 149 drawn from one of the rolls 113 or 114, as the case may be. A guard plate 150 extends across the machine between the castings 101 and 102, and is secured at its upper edge, by means of the screws 151, to the channel iron 102. The part 30 of the guard plate below the lower edge of the channel iron 102 is bent inwardly to prevent access to a knife 152, mounted to swing about a pivot 153 projecting laterally from a flange 154 formed integral with the plate 133 and projecting 35 through a slot 155 in said casting 100. The lower edge of the guard plate 150 extends close to the plate 147, so as to eliminate all possibility of the operator's hands coming in dangerous proximity to the knife 152 during the operation thereof. 40

As previously described, the plate 136 is mounted to reciprocate on the rollers 139 and has secured to the rear edge thereof a rod 156 which extends between the castings 100 and 101 to contact with the adjacent edges of the links 45 117 and 118, in order to swing these links and the plate 128, connected thereto, about the pivot rod 119 toward the stop 127. It is to be noted that the plate 128 is connected to the rod 116 at a greater radial distance from the axis of the 50 rod 119, than the rod 156, so that the plate 128 travels faster and through a greater distance in each direction than does the plate 136 during the swinging movements of the links 117 and 118. 55

The spring 124 normally holds the links 117 and 118 forwardly of the machine, and carry with them the plates 128 and 136. A stop 157 is secured to the casting 100 to limit the forward movement of the rod 156 and the plates 128 and 136. The flanges formed on opposite edges of the plate 128 have a pivot rod 158 secured thereto; and pawls 159 and 160 are pivoted to swing about the said rod 158. Each of these pawls comprises a plate 161 (see Figure 5) having flanges projecting from opposite ends thereof and apertured to receive the pivot rod 158. The front faces of each plate 161 has secured thereto a plate 162 notched at its lower edge to engage the strip of fabric 149 to prevent rearward slipping thereof 70 on the fabric during the rearward swinging movements of the said plate. The toothed edges of the plates 162 are maintained in contact with the plate 128, or the fabric lying thereon, by means of the springs 163 and 164 secured at their op- 75

posite ends to the castings 100 and 101 and to the upper edges of the said plates 161.

The knife 152 is arranged to have its cutting edge slide past the face 165 of the flange 154 upturned from the plate 133. The knife 152 is normally held in raised position (shown in Figure 6) about its pivot 153, by means of a tension spring 167 secured at one end to a pin 168 projecting from the free end of the knife 152, the other end 10 of the spring 167 being secured to a flange 169 extending from a rod 170 which projects upwardly from, and is secured at its lower end to the casting 101 (see Figure 1).

The cutting action of the knife 152 against the 15 face of the flange 154 may be regulated as shown in Figure 13 of the drawings. The flange 154 where it extends outwardly through the slot 155 is provided with a recess 171 slightly out of alignment with the cutting face of the said flange. 20 The recessed face of the flange 154 is provided with a transverse groove 172, in which is slidably mounted a small plate 173, having secured to the back thereof, a screw 174 threaded on flange 154 and provided with a lock nut 175 to hold the plate 25 173 in frictional contact with the back of the knife 152. By adjusting the screw 174, the pressure of the knife 152 against the compression spring 177 may be regulated. As shown in Figure 30 13, this compression spring surrounds the pivot screw 153 and is interposed between the forward face of the knife 152 and a pair of lock nuts 178 threaded onto said pivot 153.

The knife 152 is operated by a plunger 179 reciprocable in a cylinder 180 formed in the casting 35 126 suitably secured to the center of the channel iron 102. The plunger 179 is operated by compressed air introduced into the cylinder 180 through a pipe 181 connected to the air valve casing 57.

40 The valve casing 57 is provided with a cylindrical bore 184, in which reciprocates a cylindrical valve 185 reduced intermediate its ends to provide an outlet for compressed air through a bleed aperture 186 (see Figure 10) formed in the casing 57. In the position shown in Figures 9 and 10 of the drawings, the air under compression in the pipe 56 is cut off from pipe 181 by the leather washer 187 secured to the end of the valve 185. When the valve is moved inwardly 45 from the position shown in Figure 9, the reduced portion 188 is located with respect to the bypass 189 so that the air under compression from the pipe 56 is conducted to the pipe 181, while the bleed passage 186 is closed by the solid part of the valve 185, thereby causing the compressed air 50 to move the knife downwardly in a cutting operation.

55 The valve 185 is operated in timed relation to the movement of the plate 136 rearwardly of the machine. As shown in Figures 1 and 5 of the drawings, the plate 136 is provided with a downwardly extending flange 189 to which is secured a strap 190 (see Figure 2) which extends laterally beyond one edge of the plate 136. The strap 60 65 190 is provided with a flange 191 apertured to receive a pivot bolt 192 passing through one end of a link 193, the other end of which is pivoted to an operating rod 194 which in turn is pivoted at its upper end to a pin 195 projecting from the side 15 of the main casing of the machine. From the boss 196 at the upper end of the operating rod 194 there extends a rod 197 adapted to contact with a spherical head 198 formed on one end of a rod 199 screwthreaded axially 70 75 into the end of the piston valve 185, and locked

in adjusted position thereon by means of a lock nut 200. As shown in Figure 1 of the drawings, the operating rod 194 is provided with a series of spaced apart apertures 201 adapted to receive a pivot pin 202 connecting the link 193 5 to the rod 194. Obviously, this adjustable connection is intended to secure a proper adjustment of the rod 197 for the timed operation of the valve 185. A stop 203 extending from the side 15 in the path of movement of the rod 194 limits 10 the outward movement of the aforesaid rod and through the link 193, limits the outward movement of the plate 136.

The air pressure in the various pipes of the machine may be regulated or varied by means 15 of a pedal 205 formed on the end of a lever 206 pivoted at its rear end to a pin 207 projecting laterally from the side 15 of the main casing. The lever 206 has an angle iron strap 208 secured thereto, with horizontal flange arranged 20 to contact with a plunger 209 movable in a valve casing 210 connected by pipe line 211 to the compressed air chamber 62. The lever 206 is held in inoperative position normally by means of the tension spring 212 secured at its opposite 25 ends to the casing 15 and to the lever 206. When the pedal 205 is depressed against the tension of spring 212, the angle iron 208 operates the valve 209 to release air to the atmosphere from the compression chamber 62, and thereby decrease 30 the pressure in said chamber to the desired amount, which may be indicated on the pressure gauge 60.

In this machine, a spray of latex is intended 35 to be released only when there is an insole located in the spraying chamber in position to receive the spray. Accordingly, the pipe line 55 is provided with a plunger valve 213 adapted to be operated by pressure applied to the valve stem 214. In order to operate the valve stem the plate 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670

The air pressure used for applying the latex cement to the leather sole is preferably about forty pounds per square inch. This pressure not only divides the latex into a fine spray or mist, but also causes the sprayed latex to penetrate the fibers of the leather. When the pre-coated face of the fabric is pressed against the latexed face of the sole, the fabric becomes much more intimately connected with the leather than if the leather were merely smeared with a coating 60 of cement, or sprayed with the latex under low pressures such as have been commonly used in prior machines.

In the operation of the machine, the operator stands in front of the plate 216 which controls 65 the operation of the air valve 213 which controls the spraying of the latex. Assuming all the parts properly connected up for operation, the operator then grasps the heel of one of the soles from the shelf 98 at the side of the machine, and 70 transfers this sole laterally into the spray chamber, where it is supported by the flange 99 beneath the spraying nozzles 47 and 50. When the sole is so positioned, the operator presses the flanged edge of the plate 216 to operate the 75

valve 213, thereby forcing a spray of latex against the upturned face of the sole.

The sole is then removed from the spraying chamber and placed with the sprayed face upward on the plate 136, the operator in the meantime pulling on the strip of fabric until its end coincides with the end of the raised lip on the sprayed insole, which has been positioned with the toe thereof against the stop 143. The plate 10 136 is then pushed rearwardly against the links 117 and 118 until the link 117 contacts with the stop 127. This rearward movement of the plate 136 causes a rearward movement of the plate 128 through a greater distance than that of the 15 plate 136. This causes the roller 116 to take up slack on the fabric; and as soon as the movement is completed, the air control valve operated by the lever 194 causes operation of the plunger 179 to swing the knife 152 into a severing movement of the fabric against the cooperating flange 154 formed on the casting of the machine.

As soon as pressure is released on the edge of the plate 136, the spring 124 acting on the roller 116 swings the links 117 and 118 toward the front 25 of the machine. This forward movement locates the severed end of the fabric so that the operator may grasp the end projecting through the slot and pull it toward the front of the machine to be positioned on the next sprayed insole. The 30 pawl members 161 prevent rearward movement of the strip of fabric on the plate 128, and during the forward movement of this plate force this strip through the said slot.

In the process of spraying the inner sole, the 35 mist from the spray is taken care of by the suction fan which operates on the inside of the machine, drawing the spray in a tortuous path through a series of baffles where it coagulates. In a machine under constant operation, it is usually not found necessary to withdraw this coagulated mist oftener than once a week. What 40 drippings of latex may remain from the spraying of the inner sole, are taken care of by an opening in the bottom of the spraying chamber. This 45 opening conducts the excess latex to a removable container; and the latex thus saved may be used on an insole machine for cementing the inner sole lips.

The adjusting stop on the reciprocating plate 50 is very desirable in a machine of this character, since it can be adjusted to cause the machine to cut the fabric so exactly that the severed strip will be just level with the top of the inner sole at the strip, if it be found necessary to cut 55 so closely.

It is to be understood that the invention is not to be considered as limited to the specific construction and arrangement described herein, since it is evident that many changes may be 60 made without departing from the scope of the invention as defined by the claims appended hereto.

What I claim is:

1. A machine for applying reinforcing fabric to leather insoles comprising a supporting frame, means for rotatably supporting a roll of fabric on said frame, a plate reciprocable horizontally on said frame below said roll supporting means, means on said frame forming a guide slot for a strip of fabric from said roll, a second plate reciprocable in said frame flush with said guide slot and adapted to support and move said strip to and through said slot, means on the second plate to limit the movement of the strip in one direction, and means connecting the first named plate to the second named plate to cause the second named plate to reciprocate at a greater speed 10 and through greater distances than the first named plate.

2. A machine for applying reinforcing fabric to leather soles comprising a supporting frame, means for rotatably supporting a roll of fabric 20 on said frame, a plate reciprocable horizontally on said frame below said roll supporting means, means for limiting the reciprocation of said plate, means fixed on said frame forming a guide slot for a strip of fabric from said roll, a second plate 25 reciprocable substantially horizontally in said frame between said roll supporting means and the first named plate for feeding the strip through the guide slot, means connecting said plates to cause reciprocation by the second named plate 30 by the reciprocation of the first named plate and through greater distances in each direction, means on the second named plate to limit the movements of the strip in one direction, and a stop adjustable on the first named plate to position a sole thereon under the strip fed by the second named plate through said guide slot.

3. A machine for applying reinforcing fabric to leather soles, comprising a supporting frame, means for rotatably supporting a roll of fabric 40 on said frame, a substantially horizontal plate reciprocable on said frame, means reciprocable with said plate for feeding a strip of fabric from said roll onto said plate, and means operable by reciprocation of said plate in one direction for 45 severing the part of said strip fed onto said plate.

4. A machine for applying reinforcing fabric to leather soles, comprising a supporting frame, means for rotatably supporting a roll of fabric 50 on said frame, a substantially horizontal plate reciprocable on said frame below said roll, means reciprocable with said plate for feeding a strip of fabric from said roll onto said plate, a stop adjustable on said plate adapted to position a sole beneath the strip, and means operable by 55 reciprocation of said plate in one direction for severing that part of the strip forwardly of said stop.

JOHN A. SCOTT. 60
